157,945

COMBINED LAMP, BOOK END, AND ASH TRAY

William Davis, Hastings, Minn.

Application October 8, 1948, Serial No. 149,037

Term of patent 3½ years

(Cl. D48—20)

To all whom it may concern:

Be it known that I, William Davis, a citizen of the United States, residing at the St. Johns Hotel, Hastings, county of Dakota, State of Minnesota, have invented a new, original, and ornamental Design for a Combined Lamp, Book End, and Ash Tray, of which the following is a description, reference being had to the accompanying drawings, forming a part thereof.

Fig. 1 is a front elevational view of a combined lamp, book end, and ash tray, showing my new design;

Fig. 2 is an end elevational view of the article shown in Fig. 1;

Fig. 3 is a top plan view of the same; and

Fig. 4 is a fragmentary upper perspective view showing the shape of the recess in the base of the book end.

I claim:

The ornamental design for a combined lamp, book end, and ash tray, substantially as shown.

WILLIAM DAVIS.
